FOLDING BICYCLE EXERCISER

Charles R. Margolies, Oreland, Pa., assignor to Snyder Manufacturing Company, Philadelphia, Pa., a corporation of Pennsylvania

Filed Sept. 16, 1969, Ser. No. 19,156

Term of patent 7 years

Int. Cl. D21—03

U.S. Cl. D34—5

FIG. 3.

FIG. 5.

FIG. 4.

FIG. 1 is a side elevational view of a folding bicycle exerciser showing my new design;

FIG. 2 is a rear elevational view thereof;

FIG. 3 is a plan view thereof;

FIG. 4 is a front elevational view thereof;

FIG. 5 is a side elevational view similar to FIG. 1 but illustrating the bicycle exerciser in its folded position; and

FIG. 6 is fragmentary sectional view in perspective taken on line 6—6 of FIG. 3.

I claim:

The ornamental design for a folding bicycle exerciser, substantially as shown and described.
